UNITED STATES PATENT OFFICE.

KARL FRIEDRICH KAPPES, OF MANNHEIM, GERMANY, ASSIGNOR TO LUFTFAHRZEUG-BAU SCHUTTE-LANZ, OF MANNHEIM-RHEINAU, GERMANY.

DEFLATING AND SAFETY VALVE FOR GAS-FILLED BALLOONS.

1,408,603.

Specification of Letters Patent. Patented Mar. 7, 1922.

Application filed October 8, 1920. Serial No. 415,646.

To all whom it may concern:

Be it known that I, KARL FRIEDRICH KAPPES, a citizen of the German Republic, and resident of Mannheim, Germany, have 5 invented a certain new and useful Improved Deflating and Safety Valve for Gas-Filled Balloons, of which the following is a specification.

In the known forms of constructions of 10 valves for gas-filled balloons, as employed in connection with air-ships, the valve-disk is guided by means of a straight-line motion. Pressing the valve-disk against its seat is generally effected in these valves by means 15 of a plurality of springs which are distributed around the circumference of the seat. The pulling-device for opening the valve is arranged outside of the balloon-envelope and operates with aid of special guide rolls attached to the valve-seat vertically to the direction of motion of the valve-disk.

It has been found that the comparatively great weight of the parts constituting the straight-line motion, the springs and their 25 supporting-parts, and the guide-rolls for the valve-rope, is a drawback in the valves in question. Furthermore, the springs, owing to their ununiformity, press ununiformly upon the tightening-surface of the valve 30 whereby on closing this latter jamming of the disk or strong friction in the bearings is caused, so that the secure and tight closing of the valve is rendered dubious. Another drawback consists in the fact that, also owing 35 to the ununiformity of the springs, i. e. of their tensile power, considerable frictional resistances in the straight-line motion arise.

The power necessary for actuating the valve becomes then inadmissibly great, especially 40 with valves having comparatively long wire-ropes, as is the case with large air-vessels, so that unusual reinforcements of the valve and the valve-rope become necessary, whereby anchoring these parts is rendered more 45 difficult.

The before-mentioned drawbacks are overcome by my invention, the gist of which resides in this that the valve-disk is guided by only one lever which has its bearing, or, 50 more precisely, bearings, at the annular valve-seat and engages a rigid member secured to the center part of the valve-disk, whereas a spring which also engages said rigid valve-disk member immediately above 55 the point of connection of the said member,

and, the said lever draws the valve-disk against its seat with a pressure that is practically uniform around the whole circumference of the valve. Owing to this arrangement and combination of parts, the valve-disk cannot laterally give way so that the gas leaving the balloon through the opened valve cannot produce oscillatory movements of that disk.

In order to make my invention more clear, 65 I refer to the accompanying drawings, in which Figure 1 is a vertical section through one form of construction of the improved valve; Figure 2 is a plan of said valve; Figure 3 is a representation similar to Figure 1 70 showing a slightly modified form of construction; and Figures 4, 5, and 6, are also such representations and show some more modifications, all of which are described in detail hereinafter.

Referring to Figures 1 and 2, *a* is the cup or basin-shaped valve-disk, to the centre-part of which are secured two rigid members *b* which are connected with a lever *d* and with the lower end of a tensile spring *c*. 80 The lever *d* is supported in bearings *e* and *f* upon the valve-seat *g*, and the spring *c* is held by stays *h* *h*¹ *h*² which also are supported by the valve-seat *g*. The lever *d* is a bell-crank lever, and extends through the valve-seat in 85 opposite direction to the valve-disk *a*. *i* is a lug which is affixed to the other side of the valve-disk, also in its centre-part, and extends contrarily to the members *b*; it serves for affixing the valve-rope (*m*, Figure 3). 90 This rope may, however, be attached also to the lever-arm *d*¹.

Guiding the valve-disk by the lever *d* *d*¹, in connection with the spring *c*, affords, thus, the advantage, that the arrangement shown 95 and described may be used for free balloons, the valve-rope of which is passed through the interior of the balloon and which is pulled in the direction of the spring *c*, as well as for air-ships where the valve-rope lies 100 outside of the balloons. The friction to be overcome when operating the valve is extremely slight and the central point of engagement of the spring guarantees uniform pressing of the valve-disk against the seat-packing at every point around the circumference of the valve. Moreover, this improved valve excels the known ones by its 105 greater simplicity and lesser weight.

As but very slight frictional resistances 110

arise in the guide-parts of the valve in question, it may advantageously be employed as safety-valve. Such a form of execution is shown in Fig. 3. In this example the lever 5 d is but one-armed; the arm d^1 of Figures 1 and 2 is dispensed with. The rope m can thus be attached solely to the lug i . The rope m is, in this instance, but short and is connected with spring l attached to the 10 lower ends of bent arms k riveted to the valve-seat g . The piece of rope m is but an intermediate valve-rope; the valve-rope proper (not shown) is attached to the lower end of the spring l . If, thus, the valve-rope 15 proper is not pulled, still, the valve-disk a can be moved off its seat by an internal over-pressure arising within the balloon, independent of the valve-rope proper and of the piece of rope m and of the spring l . When, 20 then, the internal pressure and the external pressure have equalized each other, the valve closes again without any actuation of the valve-rope proper. The valve in question is, thus, capable of operating as deflating-valve, 25 as well as pressure-equalizing-valve; no special pressure-equalizing valve is necessary, whereby the weight and the costs are diminished.

In the form of construction represented 30 in Figure 4, a locking-device for the opened valve-disk is provided. When opening the valve by pulling the rope (for instance on landing or in the case of tethering of the anchoring-cable), the valve remains open 35 until the locking-means are actuated. This may be effected either by hand or by a special rope or by another pull at the same rope. Such forms of construction are shown in Figures 4, 5, and 6, of which the first shows 40 a form of execution, in which a locking-lever is to be operated by hand in order to allow of the valve closing.

1 is the locking-lever which is hinged at 2 to one of the arms k and is provided with 45 a locking-lug 3 and a locking-hook 4. A spring 5 is affixed at one end to the lever 1 and at the other end to a bracket 6, also affixed to the respective arm k . The spring 5 presses the vertical lever 1 against a horizontal lever 7 which is hinged at 8 to a bracket 9 secured to the other arm k , diametrically opposite to the bracket 6. The lever or arm 7 is drawn by the spring 7' against the lug 3 of the locking-lever 1 and 55 is connected by the piece of rope m with the lug i of the valve-disk a . The pulling-rope proper m^1 is also attached to the arm 7 so that this latter may be turned downwards by means of said rope m^1 . When doing this, 60 the pull is transmitted by the piece of rope m to the valve-disk; the valve is being opened. It is kept open because the free end of the arm 7 engages the hook 4 which is shoved upon the arm-end by the spring 5, thus locking the arm 7 and keeping the valve 65

open. The springs c and l' are correspondingly expanded and the former of them tends to close the valve, but is prevented from doing so by the hook 4. To close the valve, that is to say: to let it be closed by 70 the spring c , the hook 4 must be drawn off the arm 7 which may be effected either by hand or by a special rope that acts contrarily to the direction of action of the spring 5. 75

Referring now to Figure 5, the locking-lever 1 is a bell-crank lever having two steps 3 and 4; the lever 7 is double-armed, and the spring l'' is a pressure-spring which, normally, presses the free end of the lever 7' 80 upon the step 3 of the locking-lever 1. The spring l'' is stronger than the spring c . Besides the rope m^1 which is attached to the outer arm of the lever 7', another rope m^2 is attached to the shorter (upper) arm of the lever 1. To open the valve, the rope m^2 is pulled, when the lever 1 will be turned, the step 3 will be moved to the left, the lever 7' 85 will be turned by the spring l'' until its free end rests upon the step 4, and the valve-disk 90 will be moved off its seat by means of the piece of rope m .

In order to close the valve, the lever 7' is turned into its initial position by means of the rope m^1 . The spring l'' is, consequently, 95 compressed; the spring c draws the valve-disk against its seat, and as soon as the free end of the lever 7' arrives over the step 3, the spring 5 moves also the locking-lever 1 back into its former position (Figure 5). 100

In the form of construction shown in Fig. 6, opening and closing the valve is effected by the same rope, viz. m^1 , which is attached to a particular kind of pawl 10 10' forming an inverted V. The rope is attached to the part 10, and the part 10' forms the pawl proper which co-operates with angularly bent arms 11, of which there are four. They are firmly connected with a double-cam 12 which is arranged at an angle of 45° with respect to said arms 11. There are the locking-lever 1 with the lug 3 and the hook 4; the spring 5, and the lever or arm 7; and the co-operation of these parts is the same as in Figure 4. The cams 12 co-operate with the lower end of the lever 1; they are operated by the action of the pawl 10' upon the arms 11, and the pawl is operated by the pull exerted upon the rope m^1 . 115

The pawl 10 10' is suspended from an arm 13 which is hinged at 8 to the bracket 9' and is under the pull of a spring 14. The pawl 10 10' and the arm 13 are connected with each other by a bolt 15 which projects laterally so as to be able to push 120 upon the arm 7 and turn it, viz. in downward direction. When the rope is pulled, first the pawl 10 10' is drawn down and the arm 13 is downwardly turned; at the same 125 time the pawl proper 10' turns the cams 12 130

- by the mediation of one of the arms 11, and the spring 5 can move the locking-lever 1 as soon as the free end of the lever 7 arrives opposite to the hook 4. When the bolt 15 of 5 the downwardly moving arm 13 pushes upon the arm 7 (which is still drawn by the spring l' against the lug 3), then also this arm is moved downwards until it arrives opposite to the hook 4 over the lever 7 and 10 locks it in its present position. At the same time the valve is being opened by the mediation of the piece of rope m . It remains open because the arm 7 is now locked, as just described.
- 15 To close the valve, another pull is exerted upon the rope m^1 . The result is that another of the arms 11 is acted on by the pawl 10' and that the next cam 12 (both cams standing at present vertical in consequence 20 of the former actuation) acts upon or against the locking-lever 1, moving this latter to the left and disengaging the arm l from the hook 4. Consequently the spring l pulls the arm 7 upwards and the spring c 25 moves the valve-disk a upwards and closes the valve.
- Having now described my invention, what I desire to secure by a patent of the United States is:
- 30 1. A deflating- and safety-valve for gas-filled balloons, comprising, in combination, a valve-seat; a valve-disk; a rigid member affixed in the central part of said disk and extending in the direction towards the seat-plane; a lever supported upon said valve-seat and having its free end connected with said central member; a spring also connected with the said member and being so arranged as to be adapted to draw the said valve-disk 35 against its seat; and means to hold said spring in proper working position.
2. A deflating- and safety-valve for gas-filled balloons, comprising, in combination, a valve-seat; a valve-disk; a rigid member 40 affixed in the central part of said disk and extending in the direction towards the seat-plane; a lever supported upon said valve-seat and having its free end connected with said central member; a spring also connected 45 with the said member and being so arranged as to be adapted to draw the said valve-disk against its seat; means to hold said spring in proper working position; another spring arranged contrarily to said 50 55 first-mentioned spring outside of the valve-disk; means to hold said other spring in proper working position; a valve-opening line connected with the free end of the said other spring, as well as with the outer surface of the said valve-disk, for the purpose set forth.
3. A deflating- and safety-valve for gas-filled balloons, comprising, in combination, a valve-seat; a valve-disk; a rigid member affixed in the central part of said disk and 60 extending in the direction towards the seat-plane; a lever supported upon said valve-seat and having its free end connected with said central member; a spring also connected with the said member and being so arranged 65 as to be adapted to draw the said valve-disk against its seat; means to hold said spring in proper working position; and means to lock the said valve-disk in open position, as 70 set forth.
4. A deflating- and safety-valve for gas-filled balloons, comprising, in combination, a valve-seat; a valve-disk; a rigid member affixed in the central part of said disk and 75 extending in the direction towards the seat-plane; a lever supported upon said valve-seat and having its free end connected with said central member; a spring also connected with the said member and being so arranged 80 as to be adapted to draw the said valve-disk against its seat; means to hold said spring in proper working position; and means to lock the said valve-disk in open position, as 85 set forth.
5. A deflating- and safety-valve for gas-filled balloons, comprising, in combination, a valve-seat; a valve-disk; a rigid member affixed in the central part of said disk and 90 extending in the direction towards the seat-plane; a lever supported upon said valve-seat and having its free end connected with said central member; a spring also connected with the said member and being so arranged 95 as to be adapted to draw the said valve-disk against its seat; means to hold said spring in proper working position; and means to lock the said valve-disk in open position, as 100 set forth.
- In testimony whereof I affix my signature in presence of two witnesses.
